UNITED STATES PATENT OFFICE.

HENRY KNOELL, OF NEW YORK, N. Y.

DESIGN FOR A BUCKLE-FRAME.

SPECIFICATION forming part of Design No. 32,314, dated March 6, 1900.

Application filed January 17, 1900. Serial No. 1,800. Term of patent 7 years.

To all whom it may concern:

Be it known that I, HENRY KNOELL, a citizen of the United States, and a resident of the city of New York, borough of Brooklyn, in the county of Kings and State of New York, have invented and produced a new and original Design for a Buckle-Frame, of which the following is a full, clear, and exact description.

Reference is to be had to the accompanying drawings, forming a part of this specification, in which similar characters of reference indicate corresponding parts in all the figures.

Figure 1 is a perspective view of a buckle-frame, exhibiting my new design. Fig. 2 is an end view thereof, and Fig. 3 is a longitudinal sectional elevation taken on line 3 3 of Fig. 2.

The leading feature of my design consists in the buckle-frame, having parallel side bars and three parallel cross-bars, one of which is at one end of the side bars and the other two superposed at the other end of the side bars, the upper cross-bar having a curved raised central portion, with a recess on the side facing the single cross-bar. As shown in the drawings, the parallel side bars A are round

and curve first slightly upward and then downward from the single cross-bar A' toward the superposed cross-bars A² A³, the side bars being gradually thickened to merge into the surface of the cross-bars A² A³. Of these 30 the lower cross-bar A² is flat and the upper cross-bar A³ has a flat lower surface, forming a rectangular opening between the two cross-bars. The upper surface of the bar A³ is concaved at each side of the center, which is a 35 raised portion A⁴, having a recess A⁵ on the side facing the single cross-bar A'. The latter has two spaced downward projections A⁶.

Having thus described my invention, I claim as new and desire to secure by Letters 40 Patent—

The design for a buckle-frame, as herein shown and described.

In testimony whereof I have signed my name to this specification in the presence of 45 two subscribing witnesses.

HENRY KNOELL.
